(57) **CLAIM**

The ornamental design for an inline angle spray nozzle, as shown and described.

DESCRIPTION

FIG. 1 is a perspective view of an inline angle spray nozzle showing our new design;

FIG. 2 is another embodiment of the inline angle spray nozzle with the only difference being in the tapered ends of the nozzle tip design;

FIG. 3 is a top view of the embodiment shown in FIG. 1; FIG. 4 is a bottom view of the embodiment shown in FIG. 1;

FIG. 5 is a right side view of the embodiment shown in FIG. 1;

FIG. 6 is a left side view of the embodiment shown in FIG. 1;

FIG. 7 is a front view of the embodiment shown in FIG. 1; and,

FIG. 8 is a rear view of the embodiment shown in FIG. 1.
